UNITED STATES PATENT OFFICE.

SCOTT H. TOLMAN, OF BOSTON, MASSACHUSETTS.

AEROPLANE OR HYDROAEROPLANE CONSTRUCTION.

1,341,399.

Specification of Letters Patent. Patented May 25, 1920.

Original application filed July 10, 1917, Serial No. 179,633. Divided and this application filed June 17, 1918. Serial No. 240,273.

To all whom it may concern:

Be it known that I, Scott H. TOLMAN, a citizen of the United States, residing at Boston, in the county of Suffolk and State 5 of Massachusetts, have invented new and useful Improvements in Aeroplane or Hydroaeroplane Construction, of which the following is a specification.

This invention has for its object to provide 10 a novel structure for aeroplanes or hydroplanes, and it consists of an arrangement and construction of parts illustrated on the accompanying drawings, described in the following specification, and pointed 15 out in the appended claims.

Referring to the drawings,—

Figure 1 represents a cross section through a hydroplane embodying the invention.

Fig. 2 represents a portion of one of the 20 wings or planes on a larger scale.

Fig. 3 illustrates a portion of the frame structure.

In my copending application, Serial No. 179,633, filed July 10, 1917, of which this 25 is a division, I have illustrated and described one form of hydroplane, which is represented in cross section in Fig. 1.

For present purposes it is sufficient to state that the hydroplane comprises a boat 30 or body portion 10, wings or supporting planes 11, 11, and what for convenience I call a vertical "web" portion 12. The portions 10 and 11 form a unitary hollow structure of sufficient proportions and of sufficient buoyancy to sustain the weight of the craft when the body rests upon the water. The wings or supporting air planes project laterally from the web portion beyond the sides of the body to any desired extent. These features of construction are not essential to the present invention, which is capable of embodiment in wings or planes of any kind, and it will therefore be understood that I may embody the invention in any of the aeroplanes or hydroplanes now in use.

The present invention consists of a structure which may be used both for the body portion and for the wings or planes. It is formed of metal channel bars, preferably U-shape in cross section, which may be rolled or formed of very thin stock so as to possess a minimum weight. These channel bars are arranged to constitute

longitudinal and transverse members, as 55 indicated at 13 and 14, and are preferably, though not necessarily, perpendicular, one with relation to the other, and the ends of the transverse or spacing members (which are cut into short lengths) fit between and against the ribs or webs of the longitudinal members to which they are welded. The members thus constitute a grid, as shown in Fig. 3, which is unitary or integral, and which may be of any desired 60 length and width. In the particular form shown, the longitudinal members 13 are curved, so as to extend from tip to tip of the wings 11, this being due to the particular construction of the planes employed 65 in the hydroplane which I have illustrated. The members are arranged so that they are flush, and the fabric or sheathing which provides the supporting surface is placed upon and secured to the grid against the 70 edges of said members, that is against either the curved portions or the webs or ribs of the channel bars. For the purpose of illustration, the sheathing 15 rests against the webs or ribs of the members 13. 75 Any sheathing material may be employed, but I preferably employ very thin sheet 80 steel, and spot weld it to the members at such points as may be desirable to get the desired stability. The sheathing may be 85 above or below the grid, as desired. In a construction such as shown in Fig. 1, in which the wings increase in thickness as they approach the web portion, two grid structures are provided, one for the upper 90 portion of the wings, and one for the lower portions thereof, the web 12 and the body 10, the longitudinal and transverse members thereof forming a unitary structure, about which the sheathing is arranged as 95 desired to form a continuous skin or covering. In this case, suitable braces and struts, as at 16 and 17, may be employed in the body, as at 18 in the wings and as 100 at 19 and 20 in the juncture of the wings and the web. These struts and braces are located where they can best sustain the varying strains to which the craft is subjected, and are formed of channel bars like those at 13, 14. Their ends are welded or otherwise secured to the members of the grid or grids. Though the transverse 105 or spacing members 14 are shown as ar-

ranged in alinement with each other, they are not continuous as already stated, and hence may be offset where necessary.

5 A structure formed as herein described is very light and yet has sufficient rigidity, especially when the sheathing is formed of thin sheet steel welded together.

Having thus explained the nature of my 10 said invention and described a way of making and using the same, although without attempting to set forth all of the forms in which it may be made or all of the modes of its use, what I claim is:

15 1. An aircraft comprising metallic frame members of channel-shape cross-section arranged in angular relation, the edges of said members being outermost and in flush relation, and a sheathing of flexible sheet metal fastened to said frame against said edges.

20 2. An aircraft comprising a series of metallic frame-forming rib members arranged in substantially parallel relation, and metallic spacing members arranged between and extending transversely of said rib members, the ends of said spacing members being arranged in abutting relation to

the sides of said rib members, said rib members and said spacing members being channel-shape in cross-section and in flush relation, and a sheathing of flexible sheet metal fastened to said structure against said edges. 30

3. An aircraft comprising a frame structure including substantially parallel metallic rib members and interposed metallic 35 spacing members arranged to form a grid, said rib members and said spacing members having channel-shape cross-section and their edges being arranged in flush relation, and a sheathing of flexible sheet metal 40 welded to said edges.

4. An aircraft comprising a frame structure including substantially parallel rib members and interposed spacing members arranged to form a grid, said members being channel-shape in cross-section and having their curved portions and their edge portions respectively flush, and a sheathing of thin relatively flexible material fastened to said structure and bearing thereagainst. 45

In testimony whereof I have affixed my signature.

SCOTT H. TOLMAN.
